PORTABLE WORK TABLE

Harry B. Barrett, Clayton, Mo.
(2101 Cass Ave., St. Louis, Mo.)

Filed Jan. 19, 1959, Ser. No. 54,210

Term of patent 14 years

(Cl. D14—3)

FIG. 1

FIG. 2

FIG. 3

FIG. 4

Figure 1 is a perspective view of a portable work table embodying my new design;

Figure 2 is a side elevational view thereof;

Figure 3 is an end elevational view thereof; and

Figure 4 is a top plan view thereof.

The side not shown is the same as the side shown and the undisclosed end is of conventional configuration.

I claim:

The ornamental design for a portable work table, substantially as shown and described.
